Primary Examiner — Angela J Lee**CLAIM**

The ornamental design for a panel light, as shown and described.

DESCRIPTION

FIG. 1 is a front, left and bottom perspective view of a panel light showing my new design;

FIG. 2 is a rear, right and bottom perspective view of the panel light;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a partially enlarged view of area 9 in FIG. 2; and,

FIG. 10 is a partially enlarged view of area 10 in FIG. 4. The portions of the panel light shown in broken lines form no part of the claimed design. The broken lines encircling the enlarged areas are for annotative purposes only.
